UNITED STATES PATENT OFFICE.

ALBERT H. WHITMORE, OF NEW YORK, N. Y.

DESIGN FOR A PINCUSHION.

SPECIFICATION forming part of Design No. 33,399, dated October 16, 1900.

Application filed September 25, 1900. Serial No. 31,106. Term of patent 7 years.

To all whom it may concern:

Be it known that I, ALBERT H. WHITMORE, a citizen of the United States, residing at New York, in the State of New York, have invented and produced a new and original Design 5 for Pincushions, of which the following is a specification, reference being had to the accompanying drawings, forming part thereof.

Figure 1 is a plan of a pincushion, showing 10 my new design; and Fig. 2 is an end view thereof.

The leading or material features of my design are the tapering leg-like members at one end of the cushion, two curved or elbow-shaped members protruding from the sides, 15 and a rounded head member at the other end, said rounded head member merging by sloping sides directly into the said elbow-shaped members.

A A indicate the tapering leg-like members, 20 B B the curved or elbow-shaped members, and C the rounded head member.

d d indicate the sloping or slanting sides, which connect the sides of the head member and the elbow-shaped members. 25

The design is of approximately-elliptic contour and is ornamented to represent a partially-dressed crying baby.

What I claim is—

The design for a pincushion, substantially 30 as shown and described.

In testimony that I claim the foregoing as my invention I have signed my name in presence of two subscribing witnesses.

ALBERT H. WHITMORE.

Witnesses:

PAUL GOEPEL,
GEO. L. WHEELOCK.
